George P. COLESTON of Hartford, Connecticut
Letter Patent

The subscriber refers to an other letter patent and making a part of the same containing a description in the words of the said above Name, himself of his improvement in the machine for roasting coffee.

To all to whom these presents shall come

It is known that I above Name of the town of Hartford & the county of Hartford and State of Connecticut, have invented a new and useful improvement in a machine for roasting coffee and that the following is a full and exact description of the construction and operation of the said machine as invented and improved by me, the body consists of a circular pan or kettle of suitable size, say eight inches or more in diameter, with a concave bottom the edge of which rises twenty five or thirty degrees from the center. To the sides of the kettle two upright posts are attached directly opposite to each other, extending above the pan and connected by two horizontal braces, one at the top of the kettle and the other connecting the top of the posts through the center of these horizontal braces, an upright shaft is placed with the lower end resting on the bottom of the kettle on this shaft and so near the bottom as to prevent a grain of coffee from passing under them, are placed two long spikes end other way such as a half an inch, and long enough to extend to the side of the kettle near the top of this shaft, and on the side is placed a longitudinal wheel, with grooves enough to dent into a proportionate wheel placed on a short longitudinal shaft passing through one of the proportionate feet of said machine and another upright post carrying the two longitudinal shafts and the machine being

the center line of the bridge of the staff, or fixed a counter
balance for the purpose of turning the staff, to which the knives are
affixed, or the same may be turned by a balance weight.

My improvement consists in the application of the
knives by the special service machinery to the purpose
described, and it is for such improvement I obtain this im-
provement. The annexed design and explanations may
be referred to as exhibiting more perfectly my improvement.
